UNITED STATES PATENT OFFICE.

WILLIAM HENRY MERKLE, OF UNION HILL, AND JAMES HARRIS GERAGHTY, OF BOGOTA, NEW JERSEY.

CONTAINER LABEL AND GUARD.

1,238,551.

Specification of Letters Patent. Patented Aug. 28, 1917.

Application filed December 13, 1916. Serial No. 136,614.

To all whom it may concern:

Be it known that we, WILLIAM H. MERKLE, a citizen of the United States, and a resident of Union Hill, in the county of Hudson and State of New Jersey, and JAMES H. GERAGHTY, a citizen of the United States, and a resident of Bogota, in the county of Bergen and State of New Jersey, have invented a new and Improved Container Label and Guard, of which the following is a full, clear, and exact description.

This invention relates to means for distinguishing containers, bottles, boxes and the like, and has for an object the provision of an improved construction designed to be applied to said containers, bottles, boxes and the like whereby they may be readily distinguished either in the dark or in the light.

Another object in view is to provide a combined label and guard which will indicate the special characteristics of the matter in a container, bottle or the like, the label and guard being so formed as to be applied to the container, bottle or the like so that when grasped the label and guard will indicate the contents.

A still further object, more specifically, is the provision of a guard band having an aperture therein arranged so that the aperture will register with the label on the container, bottle, box or the like to which it is applied, and the band caused to surround said bottle, box or container whereby the information on the label may be readily seen at any time and a special structure produced for indicating the special characteristics of the contents of the bottle or container.

In the accompanying drawing:—

Figure 1 is a plan view of a guard showing an embodiment of the invention.

Fig. 2 is a transverse section through a container and a guard similar to that shown in Fig. 1.

Fig. 3 is a plan view of a slightly modified form of guard.

Fig. 4 is a plan view of a further modified form of guard to that shown in Fig. 3.

In constructing a device embodying the invention it is aimed to produce means which will not be unnecessarily unsightly and which may be quickly and easily ap-

plied to a bottle, container, box or the like, of any size or shape, and when positioned on said container will indicate the contents thereof, as for instance, poison, explosives or the like. The construction of the label and guard is such that the same will cause a person to especially observe the label on looking at the bottle or other container, or in case of darkness, when a person feels of the bottle or other container the special shape and make-up of the label will indicate that such container or the like has positioned therein poison, explosives, or some other matter of a dangerous nature.

Referring to the accompanying drawing by numerals, 1 indicates a guard provided with an aperture 2 of any desired size, which guard is intended to fit around the container 3 as shown in Fig. 2 so that the aperture 2 will substantially register with the label on the container, whereby the instructions on the label may be easily read and at the same time a guard or indicating member produced. It is to be understood that the term "container" is intended to cover bottles, boxes and receptacles of any and all kinds. A tongue or tab 5 is secured to one end of the guard in any suitable manner, as for instance, by an adhesive, said tab having thereon adhesive matter 6 so that when the tab is thrust through the aperture 7 and turned over so as to be pasted against the body of the guard, as shown in Fig. 2, the guard will be held in position on the container 3 while the adhesive 6 on the back of the guard dries.

The outer face of the guard 1 may be roughened in different ways, preferably by being provided with sand, emery or other gritty matter 8 on one face whereby when the hands are brought into contact therewith a person may immediately know that the container has some poison, explosive or other dangerous matter therein. By this means a person is positively informed as to the characteristics of the contents of the container whether it is light or dark, by reason of the touch of the guard 1. In providing the aperture 2 the guard may be used in connection with old labels and yet a proper indicating guard produced. However, if desired the guard 1 could be provided with an unsanded space 9 on which the printed matter 10 could be arranged,

said printed matter being the usual information found on a label. In this form of the invention the guard and label are of one piece and the printed matter is printed directly on part of the material making up the guard. If preferred, the guard could be provided with the aperture 2 and an ordinary label pasted on the body of the guard, either on the front or rear face. It is also evident that an ordinary label could be pasted on the body of the guard at any point, as for instance, at an unsanded central portion. In arranging the tab 5 the outer face of the body adjacent thereto may be sanded as shown in the drawing, or may be left unsanded so that the tab may be more easily pasted thereto when arranged as shown in Fig. 2, though this is not ordinarily necessary as the paste usually adheres properly to the sanded surface.

A further modified form of the invention is shown in Fig. 4 in which spaced sanded portions 11 are provided, said sanded portions being shown round in the drawing, but it will be evident that other shapes may be used without departing from the spirit of the invention.

What we claim is:

1. A guard of the character described, comprising a body having a plurality of equally spaced roughened portions arranged in rows on one side of the body, said body being formed with a slot adjacent one end and a tab extending from the opposite end of the body to said slot, said tab being provided with an adhesive end arranged to be threaded through said slot and bent over and pasted against the body when said body

is encircling an article whereby the body is held in position on said article.

2. A guard of the character described, comprising a paper body having an aperture through which a label may be seen when the guard is in position on a container, a sanded surface provided on one side of the body, and means on the opposite side of the body for connecting the body with said container, said body having an aperture at one end and a gummed tab at the opposite end designed to be threaded through said aperture and pressed against said body for locking the guard in position on the container.

3. A guard of the character described, comprising a body having a roughened surface on one side, said body being provided with a label space and a slot adjacent one end, and a tab extending from the opposite end designed to be threaded through said slot and folded upon said body when the guard is in use, said tab being provided with an adhesive on one side and adapted to lock the tab in a folded position whereby the guard will be held in position on a container.

4. A guard of the character described, comprising a body having a plurality of equally spaced roughened portions on one side of the body, said body being provided with a label space and a slot adjacent one end, and a tab extending from the opposite end of the body to said slot, said tab being designed to be threaded through said slot and bent over and pasted to the body.
